United States Patent Office

Des. 191,905
Patented Dec. 12, 1961

191,905

ILLUMINABLE ROOM DIVIDER

Jack W. Haywood, Los Angeles, Calif., assignor to Mod-
eline Company of California, Inc., Los Angeles, Calif.,
a corporation of California

Filed Apr. 24, 1961, Ser. No. 64,859

Term of patent 14 years

(Cl. D13—1)

1

FIG. 1 is a side elevational view of an illuminable room divider embodying my new design;

FIG. 2 is an end elevation thereof;

FIG. 3 is a top-plan view thereof;

FIG. 4 is a sectional view taken on line 4—4 of FIG. 1;

FIG. 5 is a similar view taken on line 5—5 of FIG. 1; and

FIG. 6 is a top plan view thereof showing the screen in a partially folded position.

The other side and end not shown are like the respective side and end shown.

I claim:

The ornamental design for an illuminable room divider, as shown and described.
